UNITED STATES PATENT OFFICE.

JOSEPH K. DAVISON, OF PHILADELPHIA, PENNSYLVANIA.

DESIGN FOR A BADGE.

SPECIFICATION forming part of Design No. 16,913, dated September 28, 1886.

Application filed February 12, 1886. Serial No. 192,462. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for Badges, of which the following is a specification, reference being had to the accompanying drawing, forming part thereof.

10 The leading features of my design for a badge are, first, a cross with a medallion formed of stars inclosed in concentric circles, and figures emblematic of charity, and next a bar.

15 A represents a cross which depends from the ribbon B, and C represents a bar to which the ribbon is attached. The cross is of the order of a Maltese cross, having at the center a medallion formed of a circular row of stars, D, and concentric circles D', inclosing the same, 20 and figures E, emblematic of charity, said figures being inclosed by the stars, and comprising in the main a soldier and sailor extending their hands over orphans in the presence of the Goddess of Liberty. The sides of the 25 limbs of the cross are curved inwardly, and the side of each limb joins the side of the adjacent limb. On the flanks are flags, an eagle,

and emblems of war. The bar C, which is of the form of a strip of greater length than height, as shown, has scrolls F G at top and bottom, and a star, H, in the bottom scroll. The face of the bar is picked, as at J. The ribbon B is striped, having a central and side stripes.

I claim—

1. A design for a badge, consisting of a cross having the central figure, E, composed of the representation of a sailor and soldier clasping hands over a kneeling child, the concentric circles D' D', and a circular row of stars, D, said 40 circles D' and stars D inclosing the central figure, and the said stars being inclosed between the said circles, the sides of the limbs of the cross being curved inwardly and joining each other, all as shown and described. 45

2. A design for a badge, consisting of a cross with a central figure, a concentric circle, a circular row of stars, a ribbon, and a bar with a scroll and stars, all as shown and described.

JOS. K. DAVISON.
